UNITED STATES PATENT OFFICE

CURT WINZER, OF HALBERSTADT, GERMANY

MACHINE FOR FORMING WAFER CORNETS

Application filed February 7, 1929, Serial No. 338,230, and in Germany February 10, 1928.

This invention relates to a machine for forming square wafer blanks into cornets and consists in the provision of an intermittently moved endless chain or the like to which conical cores are so connected that they can be deflected from a normally vertical position into contact with a laterally disposed mould composed of two hingedly connected halves, means being provided for feeding the wafer blanks automatically on to said mould so that their diagonals coincide with the hinge, and for closing the mould together with a blank about each core, means being also provided for pressing together and joining the abutting edges of the blank on the core.

Fig. 1 of the accompanying drawings represents a side view of the apparatus,

Fig. 2 is a top view of the same,

Fig. 3 is an end view in section on the line III—III of Fig. 1 showing the means for moving the cores and for connecting the edges of the blank,

Fig. 4, a section on the line IV—IV of Fig. 1 showing the blank feeding mechanism and the means for deflecting the cores,

Fig. 5, an end view showing the stripping brushes and the delivery device for the finished articles,

Fig. 6 is a section on the line VI—VI of Fig. 1 showing the main driving mechanism.

The machine comprises a main shaft 14 which receives motion through the medium of a belt pulley 15 and transmits it by means of a pinion 13 and a gear wheel 12 to a cam shaft 31. The gear wheel 12 also communicates rotation to a wheel 11 which operates, by means of bevel gears 9 and 10 and a usual driver, a Maltese cross 8 mounted on a shaft 4. The latter and another shaft 3, fitted in adjustable bearings 2 at the opposite end of the machine frame 1, carry sprocket wheels 5 and 6 whereon an endless chain 7 is supported. Equidistant brackets 16 on the chain carry conical cores whereon the cornets are to be formed. The cores are mounted on stems 19 and supported in the brackets 16 by means of trunnions 18 connected to said stems, the arrangement being such that the cores can be deflected at right angles to the radial

plane of the conveying chain. Normally the cores are maintained within said plane by a guide rail 21 which engages rollers 20 at the free ends of the stems 19. One section 22 of the guide rail is detached and mounted in a pair of toothed segments 24 which are coaxial with the trunnions 18 and which can be turned in guides 35a together with the rail section and the core in engagement with it into the position shown. A bow 23 connects the two ends of each segment 24. The segments 24 mesh with and are controlled by sectors 26 which are mounted on a shaft 25 and operated by a cam disc 30 through the medium of a link 27 and a double-armed lever 29 mounted rotatably on a shaft 28.

When a core is placed in the position shown at the top of Fig. 3, it coincides with the hinge of a conical mould 40 composed of two hingedly connected halves. The mould halves are controlled by links 50 and 51 which are pivotally connected to the mould halves and to a vertical bar 46 which is arranged to slide in a support 48. The bar is divided by a joint 47 into two parts, the lower one of which is pivoted to a bell crank 44 mounted rotatably on the shaft 28. This bell crank is operated by a cam disc 42 so as to reciprocate the bar 46 for closing the mould halves about the core 17.

Opposite the mould 40 a container 39 is mounted for the reception of square wafer blanks. A slide 38 is reciprocated across the bottom of the container so as to feed the blanks one by one onto the mould, the arrangement being such that the blanks come to rest on the mould with their diagonals over and parallel to the hinge. The slide 38 is connected by links 36 and 37 to lever arms 34 and 35 respectively which are secured to the shaft 28. The latter is rocked by an arm 33 which engages in a cam groove in a disc 32.

The cornets are formed by the mould halves 40, which for this purpose coil the blanks around and press them to the core 17. The free edges of the mould halves do not meet but leave a gap between them through which a tool can be admitted for joining the abutting edges of the wafer blank so as to complete the cornet. This joining tool con-

sists of an arm 61 which may be fitted with a detachable stamp or with a detachable plate serving as a matrix for a stamp whereby a name or the like is impressed on the joint. 5 The arm 61 rocks about a pivot 60 and is controlled by a cam disc 43 which actuates a bell crank 57, mounted rotatably on the shaft 28. One arm of the bell crank is connected by means of a ball joint 55 to a bar 53, which 10 transmits the movement to the arms 61.

All the cam discs are mounted on the shaft 31.

A pipe 71 supplies steam or a water spray whereby the wafer blanks are moistened sufficiently to allow of being coiled round the core, the spraying nozzle 70 being arranged so as to play on the lowermost blank in the container 39.

The machine is started through the medium of a hand lever 37a.

The cores with the formed cornets are taken by the chain through a channel 62 through which hot air is passed or wherein heating elements are arranged so as to dry 25 the cornets before they are delivered. The delivery is effected by means of brush rollers 66 and 67 between which the cores stop in an inverted position. The brush rollers are mounted on shafts 64 and 65 and receive motion from the shaft 31 through the medium of a belt gearing 68. An elevator 69 is arranged so as to receive the stripped-off cornets and convey them out of the machine.

The action is as follows:

35. The conveyor chain is moved intermittently by means of the Maltese cross 8 and stops the cores 17 opposite the mould 40 with their guide rollers 20 in engagement with the movable rail section 22. The freshly baked 40 wafer blanks are fed onto the mould as previously described, and each core is, after the stoppage, deflected through the medium of the segments 24, so as to come to rest on the wafer blank on the mould. Then the mould 45 halves are operated so as to close the blank about the core and form the cornet, whereupon the stamp 61 is operated so as to enter the gap between the mould halves and press the two edges of the blanks together and 50 join them. Then the mould is re-opened, and the cores restored to the upright position whereupon a new blank is fed onto the open mould, and the chain moved so as to bring the next core into operative position. The cornets 55 are taken by their cores through the drying channel 62 at the end of which they are stripped off by the brush rollers and deposited on the elevator 69, whereby they are conveyed out of the machine.

60. I claim:

1. A machine for forming square wafer blanks into cornets, comprising an endless chain, conical cores supported on said chain so as to allow of being oscillated in planes at 65 right angles to the chain, controlling means

for the cores supporting them normally in the radial plane of the chain, a conical mould divided into two hingedly connected halves arranged at one side of the chain, and maintained normally open, means for feeding the wafer blanks onto said mould so that they come to rest with their diagonals over and parallel to the mould hinge, means for moving the conveyor chain intermittently so as to stop each core opposite the mould, means for deflecting each core so as to place it over the blank on the mould, means for operating the mould halves so as to close the blank about the core, and means for applying pressure to the abutting edges of the blank so as to join them together. 70

2. A machine as claimed in claim 1, wherein the controlling and deflecting means for the cores consist of guide rails and pivoted core stems engaging said rails. 85

3. A machine as claimed in claim 1, wherein the means for deflecting the core over the mould comprises toothed segments arranged co-axially with the point about which the cores are deflected, a guide rail section carried by said segments, a stem on the core, adapted to enter into engagement with the said rail section, and means for turning the segments and rail section together with the core. 90

4. A machine as claimed in claim 1 wherein the operating means for the mould halves comprises a cam and levers and connecting rods. 95

5. A machine as claimed in claim 1 wherein the pressure applying means comprises a pivoted arm, and a cam and lever adapted to operate said arm so as to press it against the core over the abutting edges of the blank. 100

6. A machine as claimed in claim 1 wherein the pressure applying means comprises a pivoted arm, a sealing bar connected to said arm, and a cam and lever adapted to operate said arm so as to press the sealing bar against the core over the abutting edges of the blank. 105

7. A machine as claimed in claim 1 wherein the pressure applying means comprises a pivoted arm, a sealing bar connected exchangeably to said arm, and a cam and lever adapted to operate said arm so as to press the sealing bar against the core over the abutting edges of the blank. 115

8. The machine claimed in claim 1 in combination with a container for the wafers, and means for moistening the wafers as they arrive in the lowermost position in the container, the feeding means comprising a slide adapted to eject the blanks one by one from the container. 120

9. The machine claimed in claim 1 in combination with a drying channel built around part of the path along which the cores travel. 125

CURT WINZER.
